(57) **CLAIM**

The ornamental design for a lace stopper, as shown and described.

DESCRIPTION

FIG. 1 is a front perspective view of a first embodiment of my lace stopper.

FIG. 2 is a front view of the embodiment of FIG. 1.

FIG. 3 is a back view of the embodiment of FIG. 1.

FIG. 4 is a right side view of the embodiment of FIG. 1.

FIG. 5 is a left side view of the embodiment of FIG. 1.

FIG. 6 is a top view of the embodiment of FIG. 1.

FIG. 7 is a bottom view of the embodiment of FIG. 1.

FIG. 8 is another front perspective view of the embodiment of FIG. 1.

FIG. 9 is a front perspective view of a second embodiment of my lace stopper.

FIG. 10 is a front view of the embodiment of FIG. 9.

FIG. 11 is a back view of the embodiment of FIG. 9.

FIG. 12 is a right side view of the embodiment of FIG. 9.

FIG. 13 is a left side view of the embodiment of FIG. 9.

FIG. 14 is a top view of the embodiment of FIG. 9.

FIG. 15 is a bottom view of the embodiment of FIG. 9; and, FIG. 16 is another front perspective view of the embodiment of FIG. 9.

The broken lines illustrate portions of the lace stopper that form no part of the claimed design.
